DESIGN FOR FACE-PLATES FOR LOCKS.

Specification forming part of Design No. 11,239, dated June 10, 1879; application filed April 16, 1879.
[Term of patent 7 years.]

UNITED STATES PATENT OFFICE.

RODOLPHE CHRISTESEN, OF HARTFORD, ASSIGNOR TO THE RUSSELL & ERWIN MANUFACTURING COMPANY, OF NEW BRITAIN, CONNECTICUT.

DESIGN FOR FACE-PLATES FOR LOCKS.

Specification forming part of Design No. **11,239**, dated June 10, 1879; application filed April 16, 1879.
[Term of patent 7 years.]

To all whom it may concern:

Be it known that I, RODOLPHE CHRISTESEN, of Hartford, in the county of Hartford and State of Connecticut, have invented a new and useful Design for a Face-Plate of a Lock; and I do hereby declare that the following specification, taken in connection with the accompanying illustration, forming a part of the same, is a full, clear, and exact description thereof.

The novel design hereinafter described is adapted to the face-plate of a lock. It possesses the characteristic feature of being in the Japanese style of ornament.

As shown in the accompanying illustration, the plate is surrounded by a raised rim, *a*, and is divided into three main panels, *b*, *b'*, and *c*, by the latch and lock-bolt mortises. The surfaces of the upper and lower panels, *b* *b'*, are in

a plane below the rim *a*, and are dotted by slight projections. Each of the said surfaces is ornamented by a bamboo stem bearing leaves and a geometrical flower, and by a bird represented as flying.

The central panel, *c*, is ornamented by compound geometrical figures. The space between the mortises and the rim *a* is divided on each side into three panels, *d* *d'*, each of which is ornamented by narrow beads.

What I claim, and desire to secure by Letters Patent, is—

The Japanese design for the face-plate of a lock, substantially as described, and shown in the illustration.

RODOLPHE CHRISTESEN.
